(57) **CLAIM**

We claim the ornamental design for a “low profile keypad escutcheon”, as shown and described.

DESCRIPTION

FIG. 1 is a front elevational view of a low profile keypad escutcheon for a bored lock in accordance with the present design.

FIG. 2 is a back elevational view of the low profile keypad escutcheon for a bored lock seen in FIG. 1.

FIG. 3 is a left side elevational view of the low profile keypad escutcheon for a bored lock seen in FIG. 1.

FIG. 4 is a right side elevational of the low profile keypad escutcheon for a bored lock seen in FIG. 1.

FIG. 5 is a top plan view of the low profile keypad escutcheon for a bored lock seen in FIG. 1.

FIG. 6 is a bottom plan view of the low profile keypad escutcheon for a bored lock seen in FIG. 1.

FIG. 7 is a front elevational view of a low profile keypad escutcheon for a mortise lock in accordance with the present design.

FIG. 8 is a back elevational view of a low profile keypad escutcheon for a mortise lock seen in FIG. 7.

FIG. 9 is a left side elevational view of a low profile keypad escutcheon for a mortise lock seen in FIG. 7;

FIG. 10 is a right side elevational view of a low profile keypad escutcheon for a mortise lock seen in FIG. 7.

FIG. 11 is a top plan view of a low profile keypad escutcheon for a mortise lock seen in FIG. 7; and,

FIG. 12 is a bottom plan view of a low profile keypad escutcheon for a mortise lock seen in FIG. 7.

FIGS. 5, 6, 11 and 12 are shown on an enlarged scale.

The broken lines are for illustrative purposes only and form no part of the claimed design.
